FRANK W. LAWSON, OF ALGIERS, LOUISIANA.

RAIL-SUPPORTING BED.

1,073,996.

Specification of Letters Patent. Patented Sept. 23, 1913.

Application filed May 8, 1913. Serial No. 766,331.

To all whom it may concern:

Be it known that I, FRANK W. LAWSON, citizen of the United States, residing at Algiers, in the parish of Orleans and State 5 of Louisiana, have invented new and useful Improvements in Rail-Supporting Beds, of which the following is a specification.

My present invention pertains to beds or supports for railway rails, and it consists 10 in the peculiar and advantageous rail support and fastenings hereinafter described and definitely claimed.

In the drawings accompanying and forming part of this specification: Figure 1 is a 15 broken plan illustrative of a portion of a railway constructed in accordance with my invention. Fig. 2 is an enlarged detail section taken in the plane indicated by the line 2—2 of Fig. 1. Fig. 3 is a full transverse section of a construction that I prefer to employ at intervals of approximately twelve feet. Fig. 4 is a detail transverse section of an auxiliary rail brace that I prefer to employ at the outer sides of the outer rails of 20 curves with a view to resisting the outward thrust of car wheels during the passing of the train through the curve. Fig. 5 is a detail section taken in the plane indicated by the line 5—5 of Fig. 3.

Similar numerals of reference designate 30 corresponding parts in all of the views of the drawings.

In furtherance of my invention I employ under ordinary railway rails 1 longitudinal 35 supports 2 which are continuous throughout the length of the railway or such a portion of the length of the railway as a person practicing my invention may elect. The said longitudinal supports 2 are formed of 40 plastic material, preferably concrete, and formed integral with and extending between the longitudinal portions 2 at intervals of about ten feet are transverse portions 3 of concrete or other suitable plastic material.

The said transverse portions 3 serve to connect the longitudinal portions 2 and to maintain the same in the spaced relation shown in Fig. 1. Formed in the longitudinal portions 2, preferably in line with the 50 transverse portions 3, are bores 4 which merge at their outer ends in bores 5 of larger diameter as best shown in Fig. 2. Disposed at opposite sides of the rails 1 and connected to the webs thereof by bolts 6, 55 are rail supports and retainers 7. These supports and retainers extend from the

under sides of the rail heads downwardly alongside the rail webs and over the rail bases, and merge at their lower ends in vertically disposed depending portions 8. 60 These latter are embedded in the longitudinal portions 2 of the bed in transverse alignment with the bores 4 and 5, and are provided with transverse apertures 9. Extending through the bores 4 and the apertures 9 are bolts 10 which are headed at their inner ends. The outer ends of the said bolts are disposed in the bores 5, and on said ends are mounted nuts 11.

By virtue of the construction thus far described, it will be observed that a stable and durable bed is afforded for the rails, and that the rails may be expeditiously and easily fastened to the longitudinal portions of said bed, and this in such manner that 75 there is no liability of the rails being casually released from the bed or permitted to move laterally thereon.

At intervals of about twelve feet I construct the bed in the manner shown 80 in Figs. 3 and 5. By reference to these figures it will be observed that in the longitudinal portions 2 of the bed are formed outwardly and downwardly inclined bores 5^a, of oblong form or elongated form in cross-section; and it will also be observed that the apertured depending portions of the rail supports and retainers 7^a are disposed in the said bores, so as to receive headed fastening bolts 4^a, the outer 90 portions of which are carried through washer plates 12, and are equipped with nuts 13, as illustrated. In addition to permitting of ready placing of the fastening bolts 4^a, the bores 5^a serve to efficiently drain 95 the portion of the bed between the longitudinal portions 2 thereof.

At a curve in the railway, I construct the longitudinal portion 2 of the bed under the outer rail of the curve in the manner shown in Fig. 4—that is to say, I provide a kerf in the outer side of the said longitudinal portion 2, the said kerf being numbered 14, and on the longitudinal portion 2 and above the kerf I arrange the flange of a thrust-resisting plate 15. The thrust-resisting plate 15 is arranged at the outer side of the web of the outer rail and is connected thereto by a bolt or a plurality of bolts 6, 105 while the flange of the said plate is disposed above the kerf 14 so as to be secured in position by bolts 16, which are fastened to the

longitudinal portion 2 by nuts 17 disposed in the kerf 14. Obviously by reason of the provision of the kerf 14, the connection of the plate or plates 15 to the bed of the railway can be expeditiously effected.

Arranged in the longitudinal portions 2 of the concrete at intervals, say ten or twelve inches, apart are cushioning bolsters 2^a of wood, which constitute elastic supports and 10 serve to lessen the noise when a train passes over the rails. Two of the said bolsters are shown in Fig. 1, and by reference to said figure and by comparison of the full and dotted lines it will be observed that the said 15 bolsters are of dovetail form in section in the direction of the length of the portions 2; also, that the outer ends of the bolsters are backed by portions of concrete. Because of the first of said provisions the bolsters are 20 held down in the concrete. The wooden bolsters extend above the surfaces of the concrete portions in the manner common in the art and the rails 1 are preferably connected to the bolsters through the medium 25 of ordinary spikes 2^b, as illustrated.

Having described my invention, what I claim and desire to secure by Letters-Patent, is:

1. The combination in a railway, of longitudinal rail supports having upright surfaces and openings extending from said surfaces, said longitudinal portions being formed of plastic material, spaced transverse portions, of plastic material, integral 35 with said longitudinal portions, rails superposed on and extending lengthwise of the longitudinal portions, rail fasteners resting against the webs and over the bases of the rails and under the heads thereof, and fasteners connecting the first-named fasteners and the longitudinal portions or supports and having portions disposed in the said openings.

2. The combination in a railway, of a bed of plastic material comprising longitudinal rail-supporting portions having upright surfaces and also having transversely disposed openings, and spaced transverse portions, of less height than the longitudinal portions, integral with and extending between said longitudinal portions, rails superposed on the longitudinal portions of the bed, fasteners connected with the rails and having depending apertured portions embedded in the longitudinal bed portions and intersecting the said transverse openings, and connecting means extending through the said transverse openings and the apertures in the fasteners and secured in the openings.

3. The combination in a railway, of a bed of plastic material comprising longitudinal rail-supporting portions having upright surfaces and also having downwardly and outwardly inclined transverse bores extending throughout their thicknesses, and spaced transverse portions, of less height than the longitudinal portions, integral with and extending between said longitudinal portions, rails superposed on the longitudinal portions of the bed, fasteners connected with the rails and having depending apertured portions embedded in the longitudinal bed portions and intersecting said transverse inclined bores, and bolts extending through the transverse bores and the apertures in the fasteners and secured to the bed.

In testimony whereof I have hereunto set my hand in presence of two subscribing witnesses.

FRANK W. LAWSON.
